UNITED STATES PATENT OFFICE.

GEORGE H. DIMOND AND WILBUR F. DIAL, OF BRIDGEPORT, CONNECTICUT,
ASSIGNORS TO WHEELER & WILSON MANUFACTURING COMPANY, OF
SAME PLACE.

TRIMMING MECHANISM FOR SEWING-MACHINES.

SPECIFICATION forming part of Letters Patent No. 674,605, dated May 21, 1901.

Application filed January 22, 1900. Serial No. 2,249. (No model.)

To all whom it may concern:

Be it known that we, GEORGE H. DIMOND and WILBUR F. DIAL, citizens of the United States, residing at Bridgeport, county of Fairfield, State of Connecticut, have invented an Improvement in Trimming Mechanism for Sewing-Machines, of which the following description, in connection with the accompanying drawings, is a specification, like reference 10 characters on the drawings representing like parts.

This invention relates to the production of a novel trimming mechanism more especially adapted for use in trimming the edges of 15 stitched material during the stitching operation, our invention enabling close and accurate trimming to be done and enabling the operator to witness the trimming operation and see that it is done accurately.

20 Our improvements are represented as embodied in connection with a sewing-machine in which the work is supported upon a tubular arm containing, it will be supposed, any usual shuttle or equivalent device complementary to the usual needle of a stitch-forming mechanism, said tubular arm, or it may be any usual flat work-support, being cut away or recessed to form a chamber at the right-hand side, the operator facing the machine, of the slotted plate through which the feeding device operates to engage and feed the material, said chamber receiving at one 25 end a stationary cutter-blade, with which cooperates any usual trimmer-blade, the cutter-blade occupying a stationary position at the right-hand side of the usual feeding device, said blade entering, preferably, a notch in one side of the slotted plate referred to, through which the points of the feeding device pass

30 to engage the material to be fed. The upper or movable trimmer-blade is carried by a bar actuated in usual manner from a shaft in the usual overhanging arm of the machine. The chamber in the upper side of the arm or work-support leaves an open space at the right-hand side of said slotted plate in which may fall the waste removed from the stitched material, the descent of the waste from the trimmed edge of the material leaving that edge exposed to be readily seen by the operator.

Figure 1 of the drawings represents a sufficient portion of a well-known form of sewing-machine with our improvements added to enable our invention to be understood. Fig. 2 is a section in the line *x* of Fig. 1. Fig. 3 55 shows the slotted feed-plate in perspective and detached, and Fig. 4 shows the novel under or stationary cutter-blade coöperating with the usual reciprocating trimmer-blade.

It will be supposed that the arm A is tubular and that it contains a suitable shaft, as A', having at its front end a suitable pinion, as A², to engage a pinion A³ on the lower end of a shaft which in its rotation moves a suitable shuttle or loop-taker (not shown) that the 60 point thereof may enter the loop of needle-thread presented by an eye-pointed needle b, carried in usual manner by a needle-bar, as B, duly reciprocated in the head B' of the usual overhanging arm of the sewing-machine. 70

The parts so far described are and may be of any usual construction common to sewing-machines, the particular machine herein illustrated being one of the well-known Wheeler & Wilson type of tubular-arm machine. 75

The overhanging arm besides containing the usual needle-bar B also contains a presser-bar C and a cutter-bar D.

The parts so far specifically described are and may be of usual construction, and in 80 place thereof we may employ any other usual or suitable equivalents.

The exposed free end of the tubular arm A is in practice covered by a suitable shield E, of usual shape, it being represented as fitting the curved outline of the arm A, the said shield being partially broken out in Fig. 1 to show the gearing for actuating the usual shuttle or loop-taker.

In practice the shaft A' will be rotated and 90 the needle-bar and cutter-bar will be reciprocated in usual manner common to trimming attachments for use in sewing-machines, and the feeding device d², composed of a series of teeth carried by a block, may be also of 95 usual construction—for instance, the construction common to the Wheeler & Wilson sewing-machine in market.

Referring to Figs. 1 and 2, *a* represents a slotted plate having (see Fig. 3) a series of 100

slots, through which may work the feeding device d^2 , said plate being attached to the arm A by suitable set-screws, as a' . The slotted plate a is provided at its inner or right-hand side viewing Figs. 1 and 2 with a notch a^3 to receive and maintain in its proper position in alinement with the direction of feed of the material the stationary but adjustable cutter-blade c , which supports the work and co-operates with the edge d of the trimmer-blade D^4 , the said cutter-blade having a foot c' , which in the present instance of our invention has a slot c^2 for the reception of a set-screw c^3 to thereby confine the said cutter-blade in its adjusted position, said set-screw entering a suitable block a^4 , sustained within the arm A, the working part of said cutter-blade entering the notch a^3 of said plate and forming an end for said chamber, to be described. The trimmer-blade D^4 is slotted at its upper end to receive one or more set-screws, as D^3 , by which to confine the blade in any desired position vertically upon a block D^2 , the upper end of which is provided with a horizontal slot S , (see Fig. 2,) which fits over a horizontal spline g , carried by the cutter-bar D, the upper end of said block receiving through a slot therein an adjusting-screw D' , said block and the cutter D^4 carried by it being capable of being adjusted horizontally or when the screw D' is loosened to thereby place the cutting edge d of the trimmer-blade more or less distant from the vertical plane in which the needle B reciprocates, said trimmer-blade and cutter-blade being adjustable, whenever desired to occupy operative positions more or less distant from the line of action of the needle, to provide for leaving a wider or narrower margin, as may be desired, between the trimmed edge of the material and the seam uniting the different layers of material. The upper side of this arm A, or it might be a flat work-support, is cut away to leave a chamber e at one side of the line of trimming, herein represented as the inner side, said recess receiving the foot of the cutter-blade c , the recess being deep enough to expose the lower end and cutting edge of the blade D^4 , it descending at the right-hand side (see Fig. 1) of the cutter-blade c , the waste removed from the material in the operation of trimming falling into said chamber, leaving the trimmed edge of the material exposed to the view of the operator.

To prevent the work from contact with the moving or operating parts of the sewing-machine, the chamber e is provided with a cover or shield f , represented as depressed or caved centrally and as supported at its opposite ends on a portion of the arm A or work-support, the curved ends of said shield when the latter has been applied in place, as represented in Fig. 2, being confined in position by suitable gibs f^2 , which are held in place by suitable set-screws f^3 .

The presser-foot g , connected to the presser-bar by a suitable screw, is bifurcated or split

at its end in usual manner to form two toes g^3 and g^4 , the right-hand toe (see Figs. 1 and 2) being upturned to expose the work being trimmed substantially up to the line of action of the edge d of the blade D^4 .

In using the machine herein described it will be supposed that the work will be inserted under the presser-foot from its left-hand side viewing Fig. 1 and that the portion of the material to be trimmed off will project beyond the right-hand side of the cutter-blade c , and inasmuch as some of this trimming is made on sharp angles or curved lines and the trimming has to be accurate the operator by having the line of trimming and stitching thoroughly in view may by the left hand on the work at the left-hand side of the presser-foot accurately position the material preparatory to feeding it, so that the edge d of the blade D^4 will cut the material exactly in the desired line.

We have herein shown the plate a as notched at its side to receive the stationary cutter-blade c , said blade entering said notch and being maintained by the plate in proper alinement with the edge of the trimmer-blade D^4 ; but it will be obvious that our invention would not be departed from should a projection from the said plate a enter a notch suitably cut in a part of the cutter-blade.

Having fully described our invention, what we claim as new, and desire to secure by Letters Patent, is—

1. In a sewing-machine, a chambered work-support, a plate independent thereof and sustained thereby and provided with an alining-notch at its inner side, a cutter-blade independent of the walls of said chamber and provided with an angular portion constituting a foot, the cutting portion of said blade entering the alining-notch to thereby properly position the blade with respect to the plate, means for securing the foot within the work-support and a trimmer-blade co-operating with the cutter-blade.

2. In a sewing-machine, the chambered work-support, a plate independent thereof and notched at its inner side and sustained by said work-support, a cutter-blade having an angular portion constituting a foot located in said chamber, the cutting portion of the blade entering the notch on the inner side of the plate, means to secure the angular portion of the cutter-blade on the upper surface of the lower wall of said chamber, and a trimmer-blade co-operating with said cutter-blade.

3. In a sewing-machine, a work-support, a plate sustained thereby, said work-support presenting a chamber at the inner side of said plate, and having a lower wall combined with a shield centrally depressed and crossing said chamber to provide a receptacle for waste, and means to sustain said shield in operative position at a point below the surface of said plate.

4. In a sewing-machine, a slotted plate, a feeding device, a presser-foot resting on the

material on said plate, and a work-support having a chamber in its upper side next the inner side of said plate; combined with a cutter-blade located in the end of said chamber 5 next said plate, said cutter-blade having an angular foot portion by which to secure it in operative position within the chamber, a block in the lower part of said chamber to which the angular foot portion of the cutter-blade 10 is adjustably secured, and a coöperating movable trimmer-blade the end of which enters said chamber.

5. In a sewing-machine, a slotted plate, a feeding device, a presser-foot resting on the 15 material on said plate, and a work-support having a chamber at its upper side next the

inner side of said plate; combined with a cutter-blade located in the end of said chamber next said plate, a block in the lower part of said chamber to which the cutter-blade is secured, a shield secured to said work-support and crossing said chamber above said block, and a coöperating movable trimmer-blade, the lower end of which enters said chamber. 20

In testimony whereof we have signed our 25 names to this specification in the presence of two subscribing witnesses.

GEORGE H. DIMOND.
WILBUR F. DIAL.
